CLAIM

The ornamental design for a device for protection against X-rays, as shown and described.

DESCRIPTION

FIG. 1 is a top perspective view of a device for protection against X-rays according to my design;

FIG. 2 is a bottom perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines depicting stitching are directed to environment and are for illustrative purpose only. The broken lines form no part of the claimed design.
